UNITED STATES PATENT OFFICE.

FRANK IHRCKE AND HERMAN J. BRENNCKE, OF CHICAGO, ILLINOIS.

FLEXIBLE GOGGLES.

1,199,988.

Specification of Letters Patent.

Patented Oct. 3, 1916.

Application filed September 18, 1915. Serial No. 51,386.

To all whom it may concern:

Be it known that we, FRANK IHRCKE and HERMAN J. BRENNCKE, citizens of the United States, residing at Chicago, in the county of Cook and State of Illinois, have invented certain new and useful Improvements in Flexible Goggles, of which the following is a specification.

Our invention relates to eye-glasses, goggles and the like, and its object is to provide improvements in the lens connections and nose-piece construction and arrangement, designed to meet present-day demands of the trade as regards economy of construction combined with acceptable wearing appearances and operative functions.

With these objects in view the invention consists in the novel construction, combination and arrangement of parts, all as hereinabove described in detail, illustrated in the accompanying drawing, and incorporated in the appended claims.

Lens-connections, with or without separate nose-contacting portions and with or without substantial flexibility, have formed the subject-matter of numerous inventions or improvements, many of which have failed to prove commercially or practically useful by reason of prohibitive cost, complicated construction, or ungainly appearance.

In the present invention the flexibility which tends to support lenses in that normal relative relation described in Patent No. 1,118,631, is combined with the well known and simple form of rigid lens-connecting nose-piece, and is an improvement upon said patent in so far as it eliminates the practical individuality of the bridge as distinguished from the nose-bow or nose-contacting portion as a separate member.

In the present invention the continuously restrained, or substantially stopped, angular movement of the lenses provided for in Patent No. 1,118,631, is retained in distinction of the hinge connection involving the objectionable "dead" stops which formed the subject-matter of Reissue Patent No. 13,231. The old, simple form of nose-contacting bridge, or nose-piece lens-connection, is also retained, by combining therewith the substantially resisting flexibility of said Patent No. 1,118,631. In the present improvement said substantially inflexible nose-piece and flexible lens-connection are combined in a single member, which to all appearances is merely a nose-contacting bridge, by provid-

ing the ends of the latter with flexible portions which are secured to the lenses.

Our improvements further contemplate the combination of the combined flexible and rigid nose-contacting bridge with the flexible connection of Patent No. 1,118,631 minus the nose-piece, and will be more readily understood by reference to the accompanying drawing, in which—

Figure 1 is a front view of a pair of goggles embodying our invention. Fig. 2 is an enlarged top plan view of the lens-connections, the lenses being partly broken away. Fig. 3 illustrates the parts in Fig. 2 with the lenses moved angularly toward each other rearwardly. Fig. 4 is a similar view with the lenses moved forwardly. Fig. 5 is a rear view of Fig. 1 with the lenses partly broken away.

In the several views 2 and 3 represent a pair of rimless lenses provided with usual temples 4 and 5 mounted on the lenses in any suitable manner.

6 represents a nose-bow, nose-piece, or nose-contacting portion rounded in cross section of conventional arched or curved form, as shown. This nose-piece has spring ends 7 and 8 made of any suitable material having sufficient body and elasticity to normally hold the lenses in their proper relative relation while permitting relative angular movement thereof as in the case of any of the numerous well known forms of merely flexible connections. In the present instance the flexible ends 7 and 8 are shown as separate members having inwardly bent lugs or portions 9 and 10 which engage slots or recesses 11 and 12 formed in the ends of the member 6 which is of rounded cross sectional form and made of onyx, glass, celluloid, or any material which meets requirements from an artistic standpoint and for comfortable wear. We preferably give the nose-piece 6 the same coloring as the goggle lenses.

In Figs. 1 and 5 are shown rivets 13 and 14 as the means for securing the ends 9 and 10 to the nose-piece 6, though these details may be varied in any suitable manner without departing from the spirit of our invention. The opposite ends of the members 7 and 8 are bent outwardly from each other to form lens-contacting portions 15 and 16 which are secured to the lenses by means of screws or rivets 17. The ends or lugs 15 and 16 are placed against the front sides of the

lenses. An auxiliary flexible strip 18 is arranged above the nose-piece 6 and has ends 19 and 20 which are secured to the rear faces of the lenses by means of screws or rivets 21. 5 The auxiliary connection or bridge 18 has its ends bent twice at right angles so as to place the body portion 18 in line with or in front of the front faces of the lenses at the adjacent edges of said lenses. 10 The shoulders formed by the outbends 15 and 16 when in contact with the adjacent vertical edges of the lenses provide support against movements pivotally on the screws or rivets. Hence the nose-piece alone with 15 its flexible ends and with the aid of one screw or rivet at each end is capable of supporting the lenses in their proper relation. Similar shoulders formed by similar bendings of the auxiliary bridge 18 lend similar support. 20 By making use of the two bridges, or the combination nose-piece and bridge and auxiliary bridge or connection, and attaching the ends of the respective bridges to the opposite faces of the lenses a very stable relative support is lent the lenses and the resistance to flexibility in each bridge need not be more than half as much as where a single bridge is employed with a consequent lessening of strain in the parts of the lenses in 25 which the screws or rivets are inserted. 30 It will be noticed by reference to Figs. 3 and 4 that although the bridges or connections are attached to opposite faces of the lenses their flexings do not counteract each 35 other and the lenses may be folded upon each other and contained in a small case.

The nose-piece being a separate member may be conveniently given sufficient body to make it comfortable and it is not dependent 40 upon the material used to gain the connective flexibility between its ends and the lenses, but may be of whatever different material which novelty and pleasing appearance may suggest. While this double bridge 45 connection is very simple in construction the

shoulders opposite the adjacent edges of the lenses coupled with the attachment to both the opposite faces of the lenses make the connection very firm against movements on the rivets or accidental movements of the 50 lenses relative to each other.

Having thus described our invention, we claim as new and desire to secure by Letters Patent—

1. The combination with a pair of lenses, 55 of an upper flexible bridge connecting said lenses, a comparatively inflexible nose-piece arranged below said bridge, and flexible connectors attached to said nose piece and lenses, respectively, and bridging the space 60 between the ends of the nose piece and the lenses.

2. The combination with a pair of lenses, of an upper flexible bridge arranged forwardly of the rear faces of the lenses and 65 having ends which are attached to the rear faces of the lenses, a nose-piece below said bridge rearwardly of the vertical plane of said bridge, and flexible connections between the ends of said nose-piece and said lenses, 70 said flexible connections being secured to the front faces of the lenses.

3. The combination with a pair of lenses, of an upper and a lower bridge connecting 75 said lenses, each of the ends of each of the said bridges bent twice at right angles to form shoulders opposite the adjacent edges of the lenses, one of said bridges being attached to the forward faces of the lenses while the other is attached to the rear faces 80 of the lenses, one of said bridges being a continuously flexible member and the other having an inflexible and curved middle portion which serves as a nose-piece and flexible end portions. 85

In testimony whereof we have hereunto signed our names.

FRANK IHRCKE.
HERMAN J. BRENNCKE.
